METHOD OF PRODUCING BLEED LINE BY
DIFFUSION OF LIGHTOwen R. Huggins, South Norwalk, Conn., as-
signor to Linotone Corporation, a corporation
of New York

Application December 21, 1938, Serial No. 246,951

6 Claims. (Cl. 95—5)

This invention relates to the production of printing surfaces, and it is concerned more particularly with the production of printing surfaces by photography.

5 In accordance with a method already proposed a reproduction of a given design element is created on a printing member by first making a positive of the element either by hand or by photography. The positive is then placed in 10 spaced relationship with a light sensitive film or plate and subjected to the action of light to create on the film or plate a marginally reduced reproduction of the design element. The film or plate is then developed and the negative thus obtained 15 is placed in contact with one face of a screen and a second light sensitive film or plate is placed in contact with the other face of the screen. The negative is subjected to the action of light to create on the second light sensitive 20 film or plate a marginally reduced screened reproduction of the design element. Thereafter, the original positive is placed in exact register with the marginally reduced screened reproduction on the undeveloped film or plate and subjected to the action of light to create on the film or plate a full size reproduction of the design 25 element having screen lines which fall short of the outline thereof. The film or plate is then developed, and the negative thus obtained is employed in a well-known manner to create on a printing member an etched full size reproduction of the design element wherein the ground lines fall short of the boundary or outline to form a so-called bleed line.

35 While the above described method of reproducing a given design element on a printing member is satisfactory in many respects, it is open to the objection that since the element is reproduced in full size adjacent printed reproductions tend to run together or flush, this being particularly true when the reproductions are printed on textiles and the like.

The primary purpose of the present invention is to provide a photo-mechanical method of reproducing a design element on a printing member in such a manner that the reproduction is reduced marginally a distance sufficient to prevent the color from adjacent printed impressions from running together or flushing, and the ground lines fall short of the boundary or outline of the reproduction to establish a bleed line.

For a complete description as to how the improved process is carried out reference may be made to the accompanying drawing wherein 55 the design is shown, by way of example, as being

circular in form. It is to be understood, however, that the invention is not limited to the production of this particular design on a printing member, but is applicable as well to the production of other designs of different forms. 5

Referring to the drawing—

Fig. 1 is a plan view illustrating a positive of the design element;

Fig. 2 is a diagrammatic view showing the positive spaced from a light sensitive member and 10 having a source of light directed against it;

Fig. 3 is a plan view illustrating a marginally reduced negative of the design element;

Fig. 4 is a diagrammatic view showing the marginally reduced negative, an interposed screen, a 15 light sensitive member, and a source of light directed against the negative;

Fig. 5 is a plan view of the marginally reduced screened reproduction obtained on the light sensitive member shown in Fig. 4 when the negative 20 is subjected to the action of light;

Fig. 6 is a diagrammatic view showing the positive of Fig. 1 spaced from the marginally reduced screened reproduction shown in Fig. 4 and with a source of light directed against it, the spacing in 25 this arrangement being less than the spacing in the arrangement shown in Fig. 2;

Fig. 7 is a plan view showing the negative obtained after the light sensitive member shown in Fig. 6 has been developed; and 30

Fig. 8 is a plan view of the positive obtained by contact with the negative shown in Fig. 7.

In practicing the present invention, a positive 10 comprising an opaque reproduction 11 of a given design element is created on a light transparent plate 12 either by hand or by photography (Fig. 1). A transparent member 13 having a predetermined thickness is interposed between the positive 10 and a light sensitive member 14, and light from any suitable source is directed against 40 the positive 10 (Fig. 2). The reproduction 11 of the design element on the positive 10, being opaque, prevents the passage of light and, as a result a reproduction 15 of the design element on the light sensitive member 14 remains unaffected by light, but the remaining exposed portion 16 of the member becomes affected by the light which passes through the transparent portion of the positive 10 and through the interposed transparent member 13. During this exposure of the light sensitive member 14, however, the light is so directed against the positive 10 that the rays converge inwardly from the outline or boundary of the opaque reproduction 11 as they pass through the positive 10 and the intervening 50 55

member 13. In consequence, the light unaffected reproduction 15 of the design element on the light sensitive member 14 is reduced marginally a distance determined by the convergence of the 5 light rays.

After the marginally reduced reproduction 15 has been so created, the light sensitive member 14 is developed to render the reproduction 15 transparent and the light affected portion 16 10 opaque.

Thereafter, a screen 17 is interposed between the developed member or negative 14 and a second light sensitive member 18, and light is directed against the negative, preferably perpendicularly thereto (Fig. 4). The marginally reduced reproduction 15, being transparent, permits the passage of light but the remaining portion 16 of the negative, being opaque, prevents the passage of light during this exposure of the 20 second light sensitive member 18. The light which passes through the transparent reproduction 15 also passes through the transparent portions of the screen onto the member 18, and, as a result, a marginally reduced screened reproduction 20 of the design element comprising a 25 number of spaced light affected lines 21 is created on the member 18 as shown by dotted lines in Fig. 5.

A second transparent member 22 of less thickness than the transparent member 13 employed to create the first marginally reduced reproduction 15 is now interposed between the positive 10 and the still undeveloped light sensitive member 18 and the opaque reproduction 11 is centered with 30 respect to the screened reproduction 20 (Fig. 6). Then the source of light is so directed against the positive 10 that the rays converge inwardly at substantially the same angle that they did during the creation of the first marginally reduced reproduction 15. As in the previous case, the reproduction 11, being opaque, prevents the passage of light and, as a result, a reproduction 23 of the design element on the member is shielded against the action of light while the remaining exposed portion 24 of the undeveloped member 18 becomes affected by the light which passes through the transparent portion of the positive 40 10 and through the transparent member 22. The reproduction 23 on the undeveloped member 50 18 so shielded, however, is reduced marginally a distance determined by the convergence of the light rays as they pass through the transparent member 22, and since this member is thinner than the member 13 employed in the creation of the first marginally reduced reproduction 15, the reproduction 23 is reduced marginally a correspondingly less distance. Furthermore, since the screened reproduction 20 on the undeveloped member 18 is centered with respect to the opaque 55 60 reproduction 11 or the positive 10 it is also centered with respect to the reproduction 23 shielded against the action of light during this exposure of the undeveloped member 18.

After the member 18 has been so exposed it is 65 developed to render opaque the lines 21 and the portion 24 subjected to the action of light and to render transparent the light unaffected portions of the reproduction 23. The developed member or negative 18, as shown in Fig. 7, comprises a 70 transparent marginally reduced reproduction 23 of the design element having a number of opaque lines 21 which fall short of the outline or boundary thereof.

A contact positive (Fig. 8) may now be made 75 from the negative 18 and thereafter placed in

intimate contact with a light sensitive coating on a printing member and subjected to the action of light, the member treated to develop the coating, washed to remove the unaffected portions of the coating, and subjected to the action of an etching acid. The resultant etched reproduction of the design element is reduced marginally and it is provided with a plurality of spaced ground lines which fall short of the boundary or the outline of the reproduction and so provide a 10 bleed line.

By properly regulating the distance that the etched reproduction is reduced marginally and by so providing a bleed line into which empty the 15 color carrying grooves between the ground lines, printed reproductions of a given design element may be obtained which are satisfactory in every detail.

Having thus described my invention, what I 20 claim is:

1. In the art of producing printing surfaces, a process which consists in creating a positive of a design element, creating a negative of said positive reduced marginally a predetermined distance, exposing a light sensitive member to the 25 action of light projected through said negative and a screen to create thereon a screened reproduction of the negative, spacing said member from said positive with the screened reproduction centered with respect thereto, exposing said member to the action of light projected through said positive which is so spaced therefrom that a reproduction of the design element reduced marginally a distance less than said predetermined distance is shielded against the action of light 30 during exposure and then developing said member.

2. In the art of producing printing surfaces, a process which consists in creating a positive of a given design element, creating a negative of said positive reduced marginally a predetermined distance, exposing a light sensitive member to the action of light projected through said negative and a screen to create thereon a screened reproduction of the negative, interposing a transparent member between said light sensitive member and said positive with the screened reproduction centered with respect to the positive, exposing the light sensitive member to the action of light projected through said positive which is so spaced therefrom by the transparent member that a reproduction of the design element reduced marginally a distance less than said predetermined distance is shielded against the action during exposure, and then developing the exposed member.

3. In the art of producing printing surfaces, a process which consists in creating a positive comprising an opaque reproduction of a design element on a transparent plate, spacing said positive from a light sensitive member, exposing said member to the action of light projected through said positive which is so spaced therefrom that a reproduction of the design element reduced marginally a predetermined distance remains unaffected by light on said member, developing said member, exposing a second light sensitive member to the action of light projected through said developed member and a screen to create thereon a screened reproduction of the design element, spacing said positive from said second member with the screened reproduction centered with respect to the opaque reproduction, exposing said second member to the action of light projected through said positive which is so spaced from said second member that a repro-

duction thereon of the design element reduced marginally a distance less than said predetermined distance remains unaffected by light, and developing said second member.

5. 4. In the art of producing printing surfaces, a process which consists in creating a positive comprising an opaque reproduction of a design element on a transparent plate, interposing a transparent member between said positive and a light sensitive member, exposing said member to the action of light projected through said positive and said transparent member, developing said sensitized member to create a marginally reduced negative of said design element, exposing 10 a second light sensitive member to the action of light projected through said developed member and a screen to create thereon a marginally reduced screened reproduction of the design element, interposing a transparent member 15 thinner than said first mentioned transparent member between said positive and said second light sensitive member with the screened reproduction centered with respect to the opaque reproduction, exposing said second light sensitive member to the action of light projected through 20 said positive and said second mentioned transparent member, and developing the second light sensitive member to create a marginally reduced reproduction of the design element having screen 25 lines which fall short of the outline of the reproduction.

5. In the art of producing printing surfaces, a process which consists in creating a positive comprising an opaque reproduction of a design element on a transparent plate, interposing a transparent member between said positive and a light sensitive member, exposing said light sensitive member to the action of light projected through said positive and said transparent member, developing said sensitized member to create a marginally reduced negative of said design element, exposing said screen between said negative and a second light sensitive member, exposing said second light sensitive member to the action of 30 light projected through said negative and said screen to create thereon a marginally reduced 35 screened reproduction of the design element; interposing a transparent member thinner than said first mentioned transparent member between said positive and said second light sensitive member with the screened reproduction centered with respect to the opaque reproduction, exposing said second light sensitive member to the action of light projected at an angle through said positive and said second mentioned transparent member to create a marginally reduced 40 reproduction of the design element having screened lines which fall short of the outline of the reproduction.

light projected through said negative and said screen to create thereon a marginally reduced screened reproduction of the design element, interposing a transparent member thinner than said first mentioned transparent member between said positive and said second light sensitive member with the screened reproduction centered with respect to the opaque reproduction, exposing said second light sensitive member to the action of light projected through said positive 10 and said second mentioned transparent member, and developing the second light sensitive member to create a marginally reduced reproduction of the design element having screen lines which fall short of the outline of the reproduction. 15

6. In the art of producing printing surfaces, a process which consists in creating a positive comprising an opaque reproduction of a design element on a transparent plate, interposing a transparent member between said positive and a light sensitive member, exposing said light sensitive member to the action of light projected at an angle through said positive and said transparent member, developing said sensitized member to create a marginally reduced negative of said design element, interposing a screen between said negative and a second light sensitive member, exposing said second light sensitive member to the action of light projected through said negative and said screen to create thereon a marginally reduced 20 screened reproduction of the design element; interposing a transparent member thinner than said first mentioned transparent member between said positive and said second light sensitive member with the screened reproduction centered with respect to the opaque reproduction, exposing said second light sensitive member to the action of light projected at an angle through said positive and said second mentioned transparent member to create a marginally reduced 25 reproduction of the design element having screened lines which fall short of the outline of the reproduction. 30
